ROTARY CUTTER DEVICE FOR MINING MACHINES

George C. McGowan, New Brighton, Pa.

Application April 5, 1949, Serial No. 85,606

7 Claims. (Cl. 262—9)

1

This invention relates to a mining machine, and while primarily designed and intended for use in coal mining operations, it will be obvious that the apparatus may be employed for mining any other class of mineral matter, or for excavating work, or for any other purposes wherein it is found to be applicable.

Important objects and advantages of the invention are to provide a mining machine of the character described, which will function to facilitate and expedite coal mining operations, which may be constructed and operated to excavate coal to the full thickness or height of the coal vein or seam with a minimum of waste and in comparatively large chunk sizes, which is adjustable to adapt same to the varying thicknesses of coal seams, which is simple in its construction and arrangement, durable and highly efficient in its use, compact, positive in its action, and comparatively economical in its manufacture, operation, and maintenance.

With the foregoing and other objects in view which will appear as the description proceeds, the invention resides in the novel construction, combination, and arrangement of parts herein specifically described and illustrated in the accompanying drawing, but it is to be understood that the latter is merely illustrative of a preferred embodiment of the invention, and that the actual needs of practice and manufacture may require certain mechanical variations from the embodiment herein shown. It is, therefore, not intended to limit the construction of the invention of the apparatus to the disclosure thereof herein illustrated, but rather to define such limitations to the scope of the claims hereunto appended.

In the drawing wherein like numerals of reference designate corresponding parts throughout the several views:

Figure 1 is a side elevational view of a mining apparatus constructed in accordance with the invention.

Figure 2 is a plan view of one of the cutting disks and of associated parts.

Figure 3 is a sectional view taken on line 3—3, Figure 1.

Referring in detail to the drawing, the improved mining apparatus comprises a beam frame, which is designed and adapted to be supported by and projected from any suitable type of self-propelled power carriage, and operated in a manner to cause the beam frame to shift alternately in the lateral directions in an arcuate sweep.

2

The beam frame generally extends horizontally, and the forward end portion thereof is formed to provide a plurality of bearing arms 2. Each of the bearing arms carries a bearing 3 at its forward end, which bearings 3 are disposed in spaced vertical alignment. A vertically disposed shaft 4 is suitably journaled for rotation in said bearings 3.

Rotation is imparted to the vertical shaft 4 by a bevelled gear 5 and by a driving pinion 6 which is in mesh with said gear 5. The gear 5 is fixed in position on the vertical shaft, and the driving pinion is fixed on the forward end of a drive shaft 7, which latter is disposed horizontally and which is suitably journaled for rotation in bearings 8 on the beam frame 1. The rearward end of the drive shaft 7 carries a fixed transmission gear 9, which is adapted for operative engagement with the driving power mechanism employed for operating the mining apparatus.

A plurality of cutting disks, indicated at 10 and 11, are secured on the vertical shaft 4 to rotate with the latter. The cutting disks 11 are disposed at respective ends of the vertical shaft, and the cutting disks 10 are disposed intermediate of the cutting disks 11.

The cutting disks 11 have a screw thread engagement with respective ends of the vertical shaft 4 to allow the adjustment of said cutting disks 11 on the latter to meet variations in coal seam thickness. The cutting disks 11 are secured in the adjusted position on the vertical shaft by means of set screws 12, or in any other suitable manner.

Each of the cutting disks 10, 11, carries a plurality of fixed, replaceable cutter bits 13. The cutter bits are radially disposed and equally spaced and project beyond the periphery of the cutting disk in alternately staggered up and down relation to each other. Such relation of the cutter bits determines the height of the kerf cut into the coal by the operation of the cutting disks and provides clearance for the efficient operation of the latter.

The cutting disks 10, 11 are of considerable and uniform diameters, and are preferably equally spaced from each other. The number of cutting disks embodied in the apparatus is determined by the thickness of the coal seam to be mined if the entire seam is to be worked on at once, but it will be apparent that the number of cutting disks may be varied and spaced as required to best meet conditions found in practice.

55 A ripping member 14, including an eccentric

cally offset rip hook 15 having a replaceable working tip 16, is revolvably mounted on the vertical shaft 4, and is preferably disposed centrally intermediate of each pair of adjacent cutting disks. The circumferential path of travel of the rip hooks 15, when the ripping members are rotated on the vertical shaft, is considerably less than the peripheral path of travel of the associated cutting disks, and the rotating speed of the ripping members is approximately one-half of the rotating speed of the cutting disks.

Each of the ripping members 14 is rotated on the vertical shaft 4 by a system of intermeshed gearing, which latter comprises a stud gear 17, a ring gear 18, and a plurality of planetary 15 gears 19. The stud gear 17 is secured on the vertical shaft to rotate with the latter. The ring gear 18 is fixed and is secured to the adjacent bearing 3, and the planetary gears 19 are revolvably mounted on a face of the ripping member and are all disposed between and in mesh with the associated stud gear 17 and ring gear 18.

It will be evident that, by this system of gearing, when the vertical shaft is rotating, rotation in the same direction will be imparted to the ripping members, and that the gear ratio of the stud gears 17 with respect to the ring gears 18, will determine the relative rotating speed of the ripping members with respect to the rotating speed of the vertical shaft 4 and of the cutting disks 10 secured on the latter. While but one ripping member is shown between each adjacent pair of cutting disks, it will be obvious that several ripping members may be so placed, in spaced relation to each other, without departing from the principle of the invention.

In practice, the operation of the improved mining apparatus is as follows: During mining operations the beam frame 1, together with the cutting head carried thereby, is reciprocated laterally in an arcuate sweep. The apparatus will function effectively to effect coal mining operations during the travel of the device in either and both directions of its reciprocal sweep.

In the operation of the device, the cutting disks 10, 11, rotating at a comparatively high speed, will cut spaced kerfs in the face of the coal seam being worked. As the peripheries of the cutting disks extend a considerable distance beyond the ripping members 14, the cutting of the kerfs in the coal seam face will be well in advance of the operation of the ripping members.

The ripping members 14, rotating at a speed preferably approximating one-half of the rotating speed of the cutting disks, will contact with the unloosed coal disposed between adjacent kerfs, and will function to tear or rip out and dislodge all of the coal between said kerfs in a continuous operation while the device is shifting in either direction of its reciprocal swing. Due to the advance kerf cutting, the coal therebetween will be readily dislodged in large chunk sizes with a minimum of slack production. After each operative sweep of the apparatus, the coal dislodged thereby is removed in any suitable manner and method to clear the way for the next mining operative sweep of the device. At the end of each operative sweep of the device, the latter is advanced the proper distance to position the device in the proper location for effecting the next operative travel sweep in the most efficient manner.

From the foregoing description taken in connection with the accompanying drawing, the construction and method of operation of the in-

vention will be readily apparent to those skilled in the art to which the invention appertains, and it will be understood that variations in the number, location, form, proportions, and driving means of the embodied cutting disks and ripping members, may be resorted to that come within the scope of the claims.

The present invention provides a most efficient device of its kind, which may be economically 10 constructed, which will eliminate the need of under-cutting and blasting in coal mining operations, and which may be conveniently and successfully employed for the purposes and in the manner herein set forth.

What I claim is:

1. In an apparatus for mining mineral, a shiftable frame structure, a shaft revolvably supported at the forward end of said frame structure, a pair of kerf cutting disks secured on said shaft in spaced relation to each other, ripping means revolvably mounted on said shaft between said disks, a drive mechanism operable for rotating said shaft to operate said disks, and a gear mechanism mounted within said ripping means and actuated by the rotation of said shaft for imparting rotation to said ripping means, said gear mechanism including a stationary ring gear fixed to said frame structure and a stud gear fixed to said shaft to rotate with the latter and a plurality of planetary gears revolvably connected with said ripping means and meshing with said ring gear and with said stud gear.

2. In an apparatus for mining mineral, a shiftable frame structure, a shaft revolvably supported 35 at the forward end of said frame structure, a pair of spaced kerf cutting disks secured in spaced relation on said shaft to rotate with the latter, ripping means revolvably mounted on said shaft centrally intermediate of said disks, a drive mechanism operable for rotating said shaft to operate said disks and a gear mechanism mounted within said ripping means and actuated by the rotation of said shaft for rotating said 40 ripping means at a rotating speed less than the rotating speed of said disks, said gear mechanism including a stationary ring gear fixed to said frame structure and a stud gear fixed to said shaft to rotate with the latter and a plurality of planetary gears revolvably connected with said 45 ripping means and meshing with said ring gear and with said stud gear.

3. In an apparatus for mining mineral, a shiftable frame structure, a shaft revolvably supported at the forward end of said structure, a pair 55 of spaced kerf cutting disks secured in spaced relation on said shaft, a ripping member revolvably supported on said shaft between said disks, the peripheries of said disks projecting beyond the periphery of said member, a drive mechanism operable for rotating said shaft to operate 60 said disks and a gear mechanism mounted within said member and actuated by the rotation of said shaft for rotating said member at a rotating speed less than the rotating speed of said disks, said disks being adjustable on said shaft, said gear mechanism including a stationary ring gear fixed to said frame structure and a stud gear fixed to said shaft to rotate with the latter and a plurality of planetary gears revolvably 65 connected with said member and meshing with said ring gear and with said stud gear.

4. In an apparatus for mining mineral, a shiftable frame structure, a shaft revolvably supported at the forward end of said structure, a plurality 75 of kerf cutting disks secured to said shaft to

rotate with the latter, a ripping member including an eccentrically offset rip hook revolvably mounted on said shaft centrally intermediate of each adjacent pair of disks, the peripheries of said disks extending beyond said rip hooks, a drive mechanism carried by said structure operable for rotating said shaft to operate said disks, and driving means mounted within each of said members for rotating said members at a lesser speed than the rotating speed of said disks, said driving means including a stationary ring gear fixed to said frame structure and a stud gear fixed to said shaft to rotate with the latter and a plurality of planetary gears revolvably connected with said member and meshing with said ring gear and with said stud gear.

5. In an apparatus for mining mineral, a shiftable frame structure, a shaft revolvably supported at the forward end of said structure, a plurality of kerf cutting disks secured to said shaft to rotate with the latter, a pair of said disks being adjustable on said shaft, a ripping member including an eccentrically offset rip hook revolvably mounted centrally intermediate of each adjacent pair of disks on said shaft, a drive mechanism carried by said structure operable for rotating said shaft to operate said disks, and driving means mounted within each of said members actuated by the rotation of said shaft operable for rotating said members at a speed less than the speed of said disks, said driving means including a stationary ring gear fixed to said frame structure and a stud gear fixed to said shaft to rotate with the latter and a plurality of planetary gears revolvably connected with said member and meshing with said ring gear and with said stud gear.

6. A mining apparatus of the class described, comprising the combination of a shiftable frame structure, a vertically disposed shaft revolvably supported at the forward end of said structure, a plurality of uniformly spaced kerf cutting disks secured to said shaft to rotate with the latter, the disks disposed at respective ends of said shaft

being adjustable, a ripping member including an eccentrically offset rip hook revolvably mounted on said shaft centrally intermediate of each adjacent pair of disks, the peripheries of said disks extending beyond the free ends of said rip hooks, a drive mechanism carried by said structure operable for rotating said shaft to operate said disks, and driving means mounted within each of said members actuated by the rotation of said shaft operable for rotating said members at a lesser speed than the rotating speed of said disks, said driving means including a stationary ring gear fixed to said frame structure and a stud gear fixed to said shaft to rotate with the latter and a plurality of planetary gears revolvably connected with said member and meshing with said ring gear and with said stud gear.

7. In an apparatus for mining mineral, a shiftable frame structure, a pair of spaced axially aligned kerf cutting members rotatably supported by said frame structure, a ripping member rotatably supported between said pair of kerf cutting members, gear mechanism interconnecting said members for concurrent rotation including a stationary ring gear fixed to said frame structure and a stud gear connected with said kerf cutting members to rotate with the latter and planetary gear means revolvably carried by said ripping member and meshing with said ring gear and with said stud gear, said stud gear and said planetary gear means being disposed within said ripping member, and means for rotatably driving one of said members.

GEORGE C. McGOWAN.
